FERNANDO A. WESSELL, OF RED BANK, NEW JERSEY.

PIANISSIMO DEVICE FOR PLAYER PIANOS.

1,414,680.

Specification of Letters Patent.

Patented May 2, 1922.

Application filed May 19, 1921. Serial No. 470,991.

To all whom it may concern:

Be it known that I, FERNANDO A. WESSELL, a citizen of the United States, residing in Red Bank, New Jersey, have invented certain new and useful Improvements in a Pianissimo Device for Player Pianos, of which the following is a specification, reference being had to the accompanying drawing, forming a part hereof.

10 In Letters Patent of the United States, No. 566,928, dated September 1, 1896, and granted to Adam Nickel there is shown and described a device for preventing lost motion in the piano action when the soft pedal is actuated to raise the hammers into short stroke position, and in Letters Patent of the United States No. 585,829, dated July 6, 1897, also granted to Adam Nickel, there is shown and described in connection with the 15 devices for preventing lost motion, a supplemental device for assisting the proper return of the keys when the soft pedal is in operation and the hammers are raised to short stroke position. Both of these inventions were developed before the days of 20 player pianos and until now, in the development of the present invention, the lost motion preventive device and the supplemental or tension adjusting device have not been applied to player piano actions in which, as is now usually the case, the hammer rest rail, by which the hammers are supported in short stroke position as well as full stroke position, is divided in order that 25 thematic or solo effects may be produced while the hammers of one portion of the scale are in short stroke position and the hammers of the other portion of the scale, in which the melody runs, remain in full 30 stroke position. It is the object of this invention to provide means whereby the lost motion preventive device and, it may be, the supplemental or tension adjusting device also, may be applied and operated practically 35 in connection with the hammers, and, it may be, the keys also, of either portion of the scale, when the piano is being played by mechanical devices, while the hammers and keys of both portions of the scale may 40 have their action controlled by the soft pedal in the usual manner when the piano is played manually. The invention will be fully described hereinafter with reference to the accompanying drawing in which it is illustrated and in which—

Figure 1 is a top view of so much of a

piano action which embodies the invention as is necessary to enable the invention to be understood, the supporting rail for the hammer flanges being partly broken away and most of the hammers being omitted to show parts beneath.

Figure 2 is a view in section on the plane indicated by the broken line 2—2 of Figure 1, looking in the direction of the arrows, 65 the soft pedal lifter rod being partly broken out to save space.

Figure 3 is a view in end elevation as seen from the left hand in Figure 1.

Figure 4 is a detail view of means whereby the two sections of the divided hammer rest rail may be moved together.

Figure 5 is a detail view of means whereby the ends of the two parts of the lost motion preventive rod are maintained in proper 75 relation while being capable of independent operation.

Figures 6 and 7 are detail views of means for supporting the divided spring tension rod and maintaining the adjacent ends in 80 proper relation.

The hammers *a* are pivoted as usual in flanges *a'* which are supported by a fixed rail *a''*, the hammers being actuated, through the usual intermediate devices not necessary 85 to be described in detail, by the wippets *b*, which in turn are actuated through the supplemental, lost motion levers *b'*, by the usual capstan screws *c'* of the keys *c*. The hammers are supported normally by the wippets 90 slightly above the rest rail which, in a player piano, is divided, consisting of two independently movable sections *d* and *d'*. Each section, *d* and *d'*, is carried by two or more bell crank levers *d''* which are pivotally supported on the frame members *e*. The rest rail *d*, *d'* can be divided at any point which suits the piano maker, the two parts of the rail being supported independently and being operated either independently or together as conditions may require. For operation of the two parts of the rest rail together, as by the soft pedal *f* in manual playing or by a common pneumatic *f'* in mechanical playing, the two sections of the rail may 100 be provided, at adjacent ends, with fingers *d''* which may be engaged by a common lifter rod *f''*, operated either by the soft pedal *f* or by a pneumatic *f'*, in the usual manner, the pneumatic being suitably connected to 110 the vacuum system and controlling device in the usual manner, not necessary to be ex-

plained herein. As the fingers d^3 of the rest rail sections rest upon the upper end of the lifter f^2 , both sections can be moved together by the lifter f^2 or either section can be moved independently of the other.

For independent movement of either section d or d' of the rest rail, each section may be provided with a finger d^4 resting on a lifter d^5 which is controlled by a pneumatic d^6 . The latter is operated and controlled in the usual manner so that either section of the rest rail d, d' can be moved to occupy the proper relation with respect to the corresponding hammers a when in short stroke position.

One of the bell crank levers d^2 of each section d, d' of the rest rail, preferably the outer lever, is arranged to operate through an intermediate lever g in the same manner as described in the several Letters Patent above mentioned, the corresponding section of the divided lost motion preventive rod h, h' , which co-operates with the lost motion preventive levers b' above mentioned. The two sections h and h' of the lost motion preventive rod are supported by swinging arms h^2 , so as to be capable of movement separately or together, and in order that the adjacent ends of the divided rod may be held in proper relation regardless of the supporting devices, so that the rod may be divided at any point to correspond with the division of the hammer cushion rail, there is fixed in each adjacent end of the two sections a right angled finger h^3 , the bent ends of the fingers, in alignment with the bearings of the supporting arms h^2 , being received in a sleeve h^4 , which may be fixed by a set screw h^5 to one of the fingers. The ends of the rod sections are thus held in proper relation while the rod sections are free for independent movement, because the bent ends of the fingers are in line with the axis of movement and one is loose in the sleeve h^4 .

The spring tension rod or rock shaft is also formed in two sections i and i' , which are independently supported in suitable bearings indicated at i^2 , the line of division between the two sections being formed to correspond with the line of division of the rest rail d, d' and lost motion preventive rod h, h' . Each section i, i' has a flange i^3 to act, as described in said Letters Patent No. 585,829, upon the springs i^4 of the wippens b for the purpose of assisting in the return of the keys. In order that the two adjacent ends of the rod or rock shaft i, i' may be held in alignment regardless of the line of division between the two parts with respect to the supporting devices, the two adjacent ends may be bored to receive an axial pin i^5 , which maintains the two sections of the rod in alignment, but does not interfere with the independent movement of the two sections because it

is in the axis of movement and is loose in one or both sections.

It will now be understood that the two sections of the divided rest rail can be operated either independently of each other or together for the purpose of moving to short stroke position the hammers of one portion of the scale or of another portion or of moving all the hammers together, and at the same time the corresponding section or both sections of the lost motion preventive rod and the corresponding section or both sections of the tension adjusting rod, can be moved to corresponding position.

I claim as my invention:

1. In a piano action, the combination with the hammers and their actuating devices, of a divided rest rail, a divided lost motion preventive rod and co-operating devices, operative connections whereby each section of the lost motion preventive rod is actuated with the corresponding section of the rest rail and means to move the sections of the divided rest rail to short stroke position independently or together.

2. In a piano action, the combination with the hammers and their actuating devices, of a divided rest rail, a divided lost motion preventive rod and co-operating devices, operative connections whereby each section of the lost motion preventive rod is actuated with the corresponding section of the rest rail and means to move each section of the divided rest rail independently to short stroke position and common means to move 100 both sections of the divided rest rail together to short stroke position.

3. In a piano action, the combination with the hammers and their actuating devices, of a divided rest rail, a divided key compensating rod with its co-operating devices, operative connections between each section of the rest rail and the corresponding section of the key compensating rod, and means to move the sections of the divided rest rail 110 to short stroke position independently or together.

4. In a piano action, the combination with the hammers and their actuating devices, of a divided rest rail, a divided tension 115 adjusting rod with its co-operating devices, operative connections between each section of the rest rail and the corresponding section of the tension adjusting rod, means to move each section of the divided rest rail 120 independently to short stroke position and common means to move both sections of the divided rest rail together to short stroke position.

5. In a piano action, the combination with the hammers and their actuating devices, of a divided rest rail, means to support the sections of the divided rest rail independently, fingers at the adjacent ends of the divided rest rail, a common lifter for acting 130

upon both sections, and independent lifters for acting upon the sections independently.

6. In a piano action, the combination with the hammers and their actuating devices, of a divided rest rail, a divided lost motion preventive rod, means to support the sections of said rod to swing independently of each other, operative connections between the sections of the rest rail and the corre-

sponding sections of said rod, right angled 10 fingers secured to adjacent ends of said rod with their bent ends in alignment with the axis on which the sections of the rod swing, and a sleeve receiving the bent ends of both of said fingers.

This specification signed this 17th day of May, A. D. 1921.

FERNANDO A. WESSELL.
